SHEET PACK OPENER

Application filed July 19, 1928. Serial No. 293,840.

Our invention relates to improvements in sheet pack openers and it more especially consists of the features pointed out in the annexed claims.

5 The purpose of our invention is to provide an automatic machine for opening sheet packs; that separates adhering sheets as they come from the last pass, without manual intervention; that repeatedly corrugates the 10 sheets of a pack cross-wise of the traverse of the pack one corrugation at a time; that immediately reverses the corrugations; that utilizes a plurality of corrugating rolls all of which are grooved lengthwise and are rotated 15 in unison at the same speed; that succeeding corrugating rollers by acting only on a single corrugation at the same time prevents distortion and pull or stretch on the metal of the corrugation immediately following; that 20 uses a pair of feed rolls the lower one only being driven; that uses a pair of flattening rolls, the upper one of larger diameter than the lower one and the latter one only being driven; that provides vertical adjustments, 25 simultaneously operated, for the corrugating rolls, that provides a unitary drive which is attached to the opener by universal couplings for each of the positively driven rollers; and that subjects the undriven feed and flattening rolls to spring tension and adjustments independently of each other and the corrugating rolls.

With these and other objects in view we illustrate in the accompanying drawings such 35 instances of adaptation as will disclose the broad underlying features of our invention without limiting ourselves to the specific details shown thereon and described herein.

40 Figure 1 is a diagrammatic elevation of the interrelated rolls. The teeth of the corrugated rolls being shown for a part of the circumference by conventional pitch lines.

Fig. 2 is a diagrammatic front elevation of a single unit drive.

45 Fig. 3 is a diagrammatic side view of Fig. 2.

Fig. 4 is a diagrammatic top plan view of Fig. 2.

50 Fig. 5 is a diagrammatic top plan view of a double unit drive.

Fig. 6 is a side elevation of the roll housing and driving connection.

Fig. 7 is a front elevation of Fig. 6.

Fig. 8 is a top plan view of Fig. 6.

Fig. 9 is an enlarged diagrammatic elevation showing incoming and outgoing packs in relation to two sets of corrugating rolls.

In practically carrying out our invention we may use whatever alternatives of construction that the exigencies of variable service conditions may require without departing from the broad spirit of our invention as set out in a copending application Serial No. 37,421, filed on June 16, 1925.

In this instance, exemplified in the accompanying drawings, a pair of housings is used between which a pair of feeding, four pairs of corrugating, and one pair of flattening rolls are placed. These rolls are driven by a single unit or double unit drive. Of the feed rolls the lower one is shown as being driven and of the flattening rolls the lower one is also driven. All the corrugating rolls are driven in unison and in interdependence with each other so that the pack on passing from one pair of corrugating rolls to a succeeding pair will travel linearly at the same speed as the angular velocity of the rolls at the point of their engagement with the pack. These sets of corrugating rolls are so spaced, 80 pair to pair, that the rest of the entering corrugations of a pack formed transverse of its direction of travel will register with a pair of reversing corrugations of the next pair of rolls toward which the pack is advancing so 85 that each corrugation of the pack, formed one by one, will be successively reversed, one by one at the same periodicity.

The reversal of the corrugations may be carried out one or more times before they are 90 finally flattened. In the drawings four pairs of corrugating rolls are instanced which will give three reversals. It is these reversals, following each other immediately that cause the individual sheets of a pack to slide at 95 a differential rate in respect of each other which action separates them without recourse to manual operation of any kind whatever. Fig. 9 shows an arbitrary thickness of a pack. This varies with the number of sheets in a 100

5 pack and the gauge of each sheet. In practice a No. 16 gauge sheet is $1/16''$ thick, a No. 22 gauge is $1/32''$ and a No. 28 gauge is $1/64''$ thick. The whole thickness of a pack becomes a multiple of the kind of sheets that are rolled together. To compensate for this variation all the upper corrugating rolls are adjusted simultaneously in respect of their companion lower rolls and to the same extent.

10 The driving of the corrugating rolls is simplified to take care of their adjustments by a separate driving unit which is placed between the motor and the opener. It is connected to the latter by means of universal couplings, one for each driven roll. These couplings may be of any desired form or type that will cooperate most effectively in maintaining the rotation of the different rolls. As universal couplings or gimbals have become 15 so well known since their discovery by Dr. Hooke in 1600 they are not shown in detail.

20 The exemplification of one form of our invention may be described as follows: A pair of feed rolls 1 and 2 are placed above each other as shown in Fig. 1. The lower roll 1 has extensions 50 which rotate in bearing blocks 23 and the upper one has similar extensions which rotate in bearing blocks 9. As already stated the lower one is driven but if 25 desired both may be actuated. The upper roll is adjusted by screws 18 and springs 19 may be placed between the screws 18 and the bearing blocks 9 to compensate for slight variations in thickness of succeeding packs.

30 Each one of the upper corrugating rolls 3, 4, 5 and 6 are positively adjusted by means of screws 21 and 22. Rolls 3 and 5 by left hand screws 22 and rolls 4 and 6 by right hand screws 21. These screws all bear 35 against upper bearing blocks 9 in which extensions 50 of the rolls rotate and each bottom roller also has similar extensions which rotate in the lower bearing blocks 23. The flattening rolls 7 and 8 may be of different diameters, the upper one 8 being larger in order to secure added weight, and the lower one only is driven in the instance shown and it may have an increase in diameter over that of the feed rolls so as to accelerate the traverse of the pack as the corrugations are being flattened and the pack restored to its original length. Both of the flattening rolls also have extensions 50 which rotate in bearing blocks 9 and 23. The upper roll 8 is 40 adjusted by screws 20 which engage springs 21 placed between them and the upper bearing blocks 9, serving a similar purpose to the springs 19 of the feed rollers.

45 In the driving unit 31 gears 34 are connected to the upper rollers 3, 4, 5, and 6 by means of universal couplings 32 to extensions 50 and the lower duplicate rollers 3, 4, 5, and 6 are likewise driven by duplicate gears 34 which mesh with the gears 34 for the upper rolls. The lower gears are also con-

50 nected to extensions 50 of the lower rolls by means of universal couplings 32. The feed roll 2 is driven by a gear 33 through a coupling 32 and an extension 50, and the flattening roll 7 is similarly driven by a gear 35. 70 All the gears, 33, 34, and 35 are driven by idling gears 36. The center one of these is connected by a shaft 37 to a spur gear 38 positioned outside of the driving unit 31. The gear 38 may mesh with a pinion 41 on an 75 intermediate shaft 39. A spur gear 40 is attached to the shaft 39 and it meshes with a pinion 43 on the armature shaft of the motor 42 which may be supported on a suitable base independently of the unit drive 31 and bearings for the shafts of gears 38, 40, and 41 may also be placed on the motor support. 80

85 The simultaneous adjustment of the upper rolls 3, 4, 5, and 6 is simply effected by means of the screws 21 and 22 which at their upper ends have intermeshing gears 24. These gears are all actuated by a hand wheel 28 connected to a transverse shaft 27 supported in bearings 28 located on each one of the upper members 13 of the side housings 90 or frames 10. On this shaft 27 two worms shown on Fig. 7 are secured and these mesh with worm gears 25 attached to the screws 22 of corrugated rollers 5. As the hand wheel 28 is moved all the screws 21 and 22 are 95 moved in the same direction toward or from the upper bearing blocks 9. They form upper limit stops for the blocks 9. The thickness of a pack 49 determines the extent 100 the blocks 9 of the corrugated rolls are raised as the pack passes between successive pairs of such rolls.

105 The side frames 10 have end extensions 11 on which the top member 13 is secured by long fastening rods 17. The end extensions 11 are joined at their lower portion by part 12. Feet 14 are formed on the under side of 11. These feet rest on guide rails 15 to which they are secured by bolts 16. The sides 10 are held spaced apart by suitable 110 distancing tubes through which tie rods 29 pass and they are held by nuts on the outside of the frames 10. The bearing blocks 9 are held in lateral alignment as they are adjusted vertically by means of rods 30 which 115 engage vertical grooves formed in adjacent faces of the blocks 9.

120 Packs 49 are passed into the opener over feed table 46 into engagement with the feed rolls 1 and 2 which rolls deliver it to the first pair of corrugating rolls 3 where the rounded teeth 44 form depressions in the pack opposite grooves 45 of the companion rolls, gradually shortening the pack. From here the 125 pack with its first series of corrugations moves toward the second pair of rolls 4, to have its corrugations reversed and from thence continuously through between rolls 5 and 6, each pass between a pair of the rolls 4, 5, and 6 reversing the corrugations of the pack 130

as it approaches each set. If desired guides 48 may be placed between any two sets of rolls 1 and 3, 3 and 4, 4 and 5, 5 and 6, and 6 and 7, or simply between rolls 3 and 4 and 5 rolls 4 and 5. As the flattened and lengthened pack passes from between the flattening rolls 7 and 8 it is delivered over the table 47.

Microphotographs of portions of packs 10 which have been separated or opened by means of transverse corrugations immediately followed by a reversal of the corrugations and after being annealed show that the structure of the separated sheets has not been 15 damaged.

In case it is found desirable to drive all the rolls 2, 3, 4, 5, 6, and 7 from both ends, a duplicate driving unit 31 may be placed on each side of the opener, in which case the 20 shaft 39 is extended across the opener as shown in Fig. 5 and another pair of gears 38 and 41 connected to shaft 37 of the second drive unit 31. This drive is then also connected to roller extensions 50 by universal 25 couplings 32 as in the case of a single driving unit being used as shown in Fig. 4.

The immediate reversal of the corrugations of the pack is dependent on a unique relation of the cooperating parts of a pair of rolls. From Fig. 9 it will be seen that the 30 initial corrugation formed by rolls 3 depends on two adjacent teeth of the upper roll serving as a pair of anvils, separated by a groove into which the single tooth of the lower roll 35 presses the pack. In the second set of rolls, a pair of anvils or teeth 44 are on the under side of the pack causing it to traverse between these rolls on a slightly different plane from that in the first pair of rolls 3. As the pack 40 enters between rolls 5 from rolls 4 it is again slightly elevated and at rolls 6 it is subsequently slightly lowered. This relation of parts is due to the fact that the chord of contact of the pair of teeth or anvils with the 45 pack in one case is on the upper surface of the pack and in the immediately following case this chord of contact is on the under side of the pack. The difference in the two planes is approximately the same as the thickness of 50 the pack. Dotted lines U and L on Fig. 9 show this relation wherein the points of contact of upper roll 3 are indicated at 3^a and those of lower roll 4 are indicated at 4^a. In this figure hypothetical unreversed corrugations of the pack 49 are shown by dotted lines 55 adjacent rolls 4.

It is of course immaterial whether the initial adjustment of adjacent pairs of rolls compensates for this change in plane of tooth 60 contacts so as to permit the pack to pass through all the rolls on a median plane or whether it is alternately positioned on successively different planes from one set of rolls to an adjacent set. The entire province of the reversals is to cause the sheets to slip in

one direction and then to immediately slip in a reverse direction, in respect of the contact surfaces of the individual sheets of the pack.

What we claim is:

1. In sheet pack openers, a pair of frames, 70 a pair of feed rolls, a pair of flattening rolls, and several pairs of rolls having lengthwise corrugations formed thereon said rolls positioned between the feed and flattening rolls, means for simultaneously driving the corrugated rolls and separately driving one of the feeding and one of the flattening rolls, separate bearings for each roll end, means for separately adjusting the bearings of the upper feed and flattening roll, and means for simultaneously adjusting all the bearings of the upper corrugated rolls to the same extent. 80

2. In sheet pack openers, an opener unit 85 comprising a pair of suitable frames, a plurality of upper and lower bearings in each frame, a plurality of feed flattening and corrugated rolls rotatable in the bearings, means for limiting the upward movement of the upper bearings of the feed and flattening rolls 90 independently of each other, and separate means for limiting the upward movement of the bearings at both ends of the upper corrugated rollers simultaneously and to the same extent. 95

3. In sheet pack openers, an opener unit comprising a pair of feed rolls, a pair of flattening rolls, several pairs of rolls having lengthwise corrugations formed thereon, a pair of side frames, bearings in such frames 100 for all the rolls, a motor, unitary driving unit between the motor and a side frame, driving connections from the motor through the unit to the rolls, separate universal connections from the driving unit to the rolls whereby 105 the position of one half of the corrugated rolls can be changed in respect of the other half while being driven by the unit, and means for interconnecting the several rolls with the driver so that all the corrugated 110 rolls will rotate in unison.

4. A sheet pack opener comprising a plurality of pairs of lengthwise corrugated rolls in excess of two pairs, held for rotation in adjacent spaced apart relation, means for adjusting the position of both ends of one half of such rolls, in respect of the other half simultaneously, a separate pair of feed rolls, a separate pair of flattening rolls, means for rotating the different lower corrugated 115 rolls in unison without changing their unitary driven relation, and means for only driving the lower feed and the lower flattening rolls. 120

5. A sheet pack opener comprising a pair 125 of rolls corrugated lengthwise thereof, another pair of rolls similarly corrugated, the teeth of one roll of each pair registering with the space between adjacent teeth of the other roll, other pairs of rolls corrugated in like 130

manner, means for rotating all the rolls in unison, means for so connecting the rolls to the actuating means that the median tooth position of succeeding pairs of rolls is alternately reversed, thereby causing the teeth of a succeeding pair of rolls to depress the raised portion formed by the pair of rolls immediately preceding.

- 5 6. In sheet pack openers, a plurality of pairs of corrugated rolls, means for feeding a sheet pack to a pair of corrugated rolls whereby the length of the pack is shortened through the formation of transverse corrugations in the pack, means for continuing the traverse of the pack from one set of rolls to another whereby the previously formed corrugations are immediately reversed, thereby causing the sheets composing a pack to slide in respect of each other, means for lengthening the shortened pack to remove the corrugations, means for simultaneously adjusting the distance between the rolls of each pair simultaneously in accordance with the thickness of the pack and means for driving all the 20 rolls in unison.

- 25 7. In sheet pack openers a plurality of pairs of interactuated rolls corrugated lengthwise thereof, a pair of smooth feed rolls, and a pair of smooth flattening rolls the upper one being of larger diameter than its lower driven roll, the relation of all the rolls being such that the sheet pack which is to be opened first passes between the feed rolls then successively between the pairs of corrugated rolls and finally between the flattening rolls.

- 30 8. In sheet pack openers, a plurality of pairs of upper and lower interactuated rolls corrugated lengthwise thereof, a pair of feed rolls, a pair of flattening rolls, a single driving unit for actuating the rolls simultaneously, and a separate motor unit connected to the driving unit, the position of the rolls and their relation of operation being such that a sheet pack first passes between the feed rolls then between pairs of corrugated rolls, and lastly between rolls for flattening the corrugations.

- 35 9. In sheet pack openers, a pair of feed rolls, a pair of delivery rolls, a plurality of pairs of rolls corrugated lengthwise thereof positioned between the feed and delivery rolls, positive means for simultaneously adjusting both ends of all of the the upper corrugated rolls, separate adjusting means for the upper feed and the upper delivery rolls, and elastic means interposed in the adjusting means for the latter rolls, which arrangement of parts serves to receive a sheet pack between the feed rolls, pass it between pairs of corrugated rolls and finally pass the pack between flattening rolls for delivery from the opener.

40 In testimony whereof we affix our signatures.
